UNITED STATES PATENT OFFICE.

SHANE ETHEL LEIBSON, OF ST. LOUIS, MISSOURI.

SUN VISOR.

Application filed March 9, 1927. Serial No. 173,866.

My invention relates to improvements in sun visors and has for its primary object a sun visor which is intended to take the place of a cap and which is so constructed that, while the head will be perfectly ventilated and exposed to the atmosphere, the eyes of the wearer will be shaded and the forehead of the wearer will be protected against sun-burn.

10 A further object is to construct a device to take the place of a cap in which the head of the wearer will be exposed to the atmosphere and which is provided with a permanently fixed eye shade or visor and with a pivotally 15 and detachably mounted visor so that the last mentioned visor can be utilized both for protecting the back of the neck of the wearer or to protect the forehead of the wearer.

A still further object is to construct a sun 20 visor in which a double visor is provided, the second visor being detachably and pivotally secured in position so that both visors can be made to overlap, and the wearer of the device may have either a long or short 25 visor for protecting his eyes.

In the drawings:

Fig. 1 is a side elevation of my device showing the same with the visors in opposite 30 positions in solid lines, and one of the visors in position to protect the forehead of the wearer against sun-burn.

Fig. 2 is a perspective view of my device with both visors overlapping each other so as to create a longer visor; and

35 Fig. 3 is a fragmental view of the straps which fit over the head of the wearer illustrating the sliding adjustment necessary for various shaped heads, and

40 Fig. 4 is an enlarged section taken on the line 4-4 of Fig. 1.

In the construction of my device I employ a band 4 which is preferably made of celluloid or similar material and which has its edges provided with a binding 5. This binding 45 is secured by means of stitching or similar fastening means although adhesive may be employed, if desired.

The band 4 has its ends 6 and 7 unattached to each other and between these ends a strip 50 of elastic material 8 extends so that the band can expand and adjust itself to various head sizes. Carried by the band 4 are members 9, 10 and 11 which are arranged as illustrated in Fig. 2 and which prevent or limit the 55 downward movement of the band 4. The member 11 is provided with a slot 12 through

which the members 9 and 10 pass thereby adjustably holding the members together at their crossing point. Secured to the band 4 is a visor 13 which is preferably made of celluloid or similar translucent material suitably colored so that while perfect vision can be had therethrough, the light rays or sun rays passing therethrough will not blind the wearer.

The visor 13 is preferably provided with a binding 14 which not only eliminates rough edges but also serves as a stiffening member. The band 4 is provided with one portion of a glove fastener which is adapted to receive the complementary portion 15 of said fastener. This complementary portion is secured in a band 16 which is provided with a binding 17. The band 16 carries a visor 18 which has its edges protected by a binding 19. The visor 18 being of greater width than the visor 13 as illustrated in Fig. 2, the purpose of which will be hereinafter described.

It will be understood by reason of the 80 glove or snap fastening employed that the visor 18 is pivotally mounted so that it can be swung into the position indicated by dotted lines in Fig. 2 and when in this position will protect the forehead of the wearer 85 against sun-burn, and by reason of the glove fasteners it is also possible to entirely disconnect the visor 18 and wear my device without it or, in the event that additional shading of the eyes is desired, the visor 18 90 can be placed in the position indicated in Fig. 2 thus giving a longer visor.

My purpose in slotting the member 11 and passing the members 9 and 10 therethrough is to permit the same to readily adjust themselves to various head shapes as I have found that, where these members were secured together by means of a rivet or the like, undue strains were set up and these members or straps would not readily adjust themselves 100 to accommodate head shapes.

I am aware that sun visors have been on the market which were provided with straps fitting over the head, a strap surrounding the head and with an eye shade. However 105 there were serious objections to these devices because there was no adjustability of the straps which extended over the head to conform to various head shapes. There was no resiliency in the band which fitted around 110 the head of the wearer.

Furthermore there was no way of protect-

ing the forehead of a wearer against sun-burn, that is, that portion of the forehead above the band 4, and again there was no way in which the back of the neck of the wearer could be protected against sun-burn. This last mentioned feature has been specially stressed by golfers because they wanted a device which was cool and which would not only protect their eyes against the glare of the sun but also protect the back of the neck against sun-burn. With my device all of these requirements are met, as well as affording, in certain instances, protection against sun-burn on the forehead.

15 Another important feature of my structure is that my device can be easily used in the driving of automobiles and is especially useful either early in the morning or late at night when driving directly toward the sun because by reason of being able to lengthen the visor by means of the glove fastener connection, I am enabled to shade the eyes of the driver and to prevent him from being blinded by the sun. In short my device embodies a sun visor to take the place of a cap

which is provided with a detachable auxiliary visor, which visor may be either pivoted on this fastening or detached and reversed so that it will meet many conditions now required by wearers of the devices.

Having fully described my invention, what I claim is:—

A sun visor comprising a head encircling band, a plurality of members having their ends secured to said band at diametrically opposite points so that said bands will cross each other and limit the downward movement of said head band, a visor secured to said band, a second band of less length than said first mentioned band, a visor secured to said second mentioned band, and fastening devices carried by said first mentioned band and the ends of the second mentioned band for detachably securing said bands together whereby the visor carried by the second mentioned band can be secured in various positions on said first mentioned band.

In testimony whereof I have affixed my signature.

SHANE ETHEL LEIBSON.
